United States Patent Office.

WILLIAM H. OVERHISER, OF STOCKTON, CALIFORNIA.

Letters Patent No. 66,990, dated July 23, 1867.

IMPROVEMENT IN HAY-ELEVATOR.

The Schedule referred to in these Letters Patent and making part of the same.

TO ALL WHOM IT MAY CONCERN:

Be it known that I, W. L. OVERHISER, of Stockton, in the county of San Joaquin, and State of California, have invented a new and improved Hay and Grain-Elevator; and I do hereby declare that the following is a full and exact description thereof, reference being had to the accompanying drawings, and to the letters of reference marked thereon.

This invention consists of a derrick suitably supported in a portable frame, and acting in combination with pulleys and a rope in such a manner that a pair of horse hay-forks can be kept constantly at work stacking hay or grain or transferring grain from the stack to a threshing machine, as is hereinafter described.

To enable others skilled in the art to make and use my invention, I will now proceed to describe its construction and operation.

A represents a pair of sills or runners of stout timber, in each of which is fixed a suitable number of standards, B, and on which rests a suitable number of cross-ties, C. D represents a flat table supported by the standards B and the cross-braces E. F represents a pivoted bar provided with journals at each end, which lie in boxes a', one on each sill, near the forward end thereof. G represents a derrick stepped in the pivoted bar F, supported in the usual manner by guys b, and provided with a pair of pulleys, H, at its top. A recess, c, is made in the table D for the accommodation of the derrick. The sills, table, standards, etc., constitute a portable frame in which the derrick may be transported from place to place. When *en route* the guys and other apparatus are placed upon the table, and the derrick leans against the edge thereof at the inner extremity of the recess c. I represents a rope passing about the pulley K, placed at any convenient distance from the framework. The rope runs thence under the double block L, one part under each sheave, and thence over the pulleys H H, one part over each sheave. The ends of the rope are attached each to one of the large forks M. This rope is a unit, and consequently if either side of the pulley K receives motion the other part must also move. The motive power is applied to either part of the rope at pleasure between the pulley K and the framework, as at d. Horse-power is usually applied. Suppose one of the forks to be on the stack ready to take its load and the other to have delivered its load to a threshing machine stationed at the side of the framework. Suppose also that at this juncture the horse is at the point of his beat farthest from the framework at the right of the pulley K and advances toward the framework. In that case the fork on the stack is drawn toward the machine and at the same time the fork that has just delivered its load is lowered, and as the horse advances is drawn by its operator back on the stack, at which, when it has arrived, the horse has attained the limit of his beat and the other fork has reached the proper place for delivering its load, supposing the rope to have the proper length and the pulley K to be placed at the proper distance from the framework. On the return of the horse toward the pulley K the same process is gone through with. Thus it will be seen that both forks move simultaneously in opposite directions at an expenditure of power very little greater than would be required to move one and accomplish double the amount of work that a single fork could accomplish. These results are due to the peculiar arrangement of the single rope and the pulleys and block, whereby the usual more complicated and expensive system of single or double drums and vertical and horizontal spur-gearing employed to effect a simultaneous motion of two hoisting devices in opposite directions is dispensed with. It will also be seen that the horse is not subject to the painful and wasteful process of backing.

Having thus described my invention, what I claim as new, and desire to secure by Letters Patent, is—
The single rope I, in combination with the pulleys H and K and the block L, for the purpose of effecting the simultaneous motion of the forks M in opposite directions, substantially as described.

WM. L. OVERHISER.
